COKE-TREE BREAKER

Arthur K. Knudsen, Oak Park, and Arthur V. Sampsel, Spring Valley, Ill., assignors to Sears, Roebuck and Co., Chicago, Ill., a corporation of New York

Application June 20, 1941, Serial No. 398,866

3 Claims. (Cl. 110—32)

Our invention has to do with fire agitators. The purpose of this apparatus is to provide in connection with a standard or any other stoker motor installation, which, if desired, may include a hold-fire switch and/or an out-fire switch, means for agitating the coke-tree forming in the burner. This is of importance wherever stokers use coal of high coking characteristics. Such coal forms a coke-tree in the burner, and this coke-tree increases in size as more coal is fed, until it blocks further combustion and puts the fire out. The coke-tree, if permitted, will substantially fill the fire-box and, when it cools, it expands and is likely to break the walls of the fire-box. Moreover, it is a difficult and time-consuming task to clean the fire-box of the accumulated coke.

By means of the apparatus about to be described, the coke-tree which forms during and between successive feedings of coal is broken and mixed with green coal which burns to a sufficiently high temperature to also burn the coke.

In the past, it has been the practice, where furnaces were equipped with such agitators, to locate the agitator within the furnace. This made access difficult and inconvenient. Moreover, it has been the practice to so connect the agitator with the stoker that when the agitator became inoperative, the stoker also was inoperative and the stoker could not be made to operate until after the agitator again became operative.

In accordance with the present invention, the agitating member is mounted outside of the furnace and in a position where it is easily accessible for repair or adjustment without necessitating opening of the furnace. Another important feature is that the stoker is independent of the operation of the agitator, so that should the agitator be put out of operation for one reason or another, the stoker will continue to operate as if nothing had happened.

Another disadvantage of past agitator constructions is that there is a likelihood of the agitator's stopping within the burner or fire-box and becoming burned, or of the coke's freezing around the agitator so as to prevent the agitator from operating the next time it is supposed to operate. With the present construction, as will be seen, the agitator is necessarily removed from the fire at the close of each agitating operation.

Further objects and advantages of our invention will appear as the description proceeds.

The invention will be better understood upon reference to the following description and accompanying drawing, in which:

Fig. 1 is a schematic view, partly in section, of an agitator and control therefor, embodying features of our invention, taken partly as indicated by the line 4—4 in Fig. 4.

Fig. 2 is a broken elevation showing an agitator in a stoker and furnace assembly.

Fig. 3 is a section-elevation taken as indicated by the line 3—3 in Fig. 1.

Fig. 4 is a diagrammatic plan view taken as indicated by the line 4—4 in Fig. 1. Fig. 5 is a sectional view taken as indicated by the line 5—5 in Fig. 1.

Referring more particularly to Fig. 1, showing one form of agitator system embodying our invention, there is operated either from the line 6 or other energy source a clock (not shown) which turns a cam 11, having vanes 12 and rotating once an hour, for example, or any other suitable period. A hand switch 7 and a fuse 8

20 may be disposed in said line. The cam 11 could be operated by the same clock operating the hold-fire switch, if such hold-fire switch is used in the stoker installation to which our invention is applied. The number of vanes 12 may be varied 25 as desired, say from 1 to 2 to 4, depending of course on the frequency with which it is considered desirable to agitate the fire. This frequency may vary with the coking characteristics of the fuel, the size of the fire, and for other 30 reasons. Each vane is designed and arranged to close a switch 14, mercury tube or other suitable switch for any desired period, say, one second. This period is mentioned by way of example because as will be understood by those skilled in

35 the art the duration may be varied. The switch 14 is normally held open as by a spring 15, to an extent limited by the inherent shape of the switch blade or as by a stop 16. The switch 14 is in series with a relay coil 18 which is in series 40 with a transformer secondary coil 19. When the switch 14 is closed, the relay coil 18 closes a relay switch 20, thereby closing a circuit which includes a motor 21.

Connected to the motor 21 as through reduction gearing (not shown) is a cam 22 which is rotated at the rate of, say, once in five seconds. This cam has a "make" shoulder 24 which is engageable with a bell crank lever 25 pivoted at 26, to tilt and close a mercury tube switch 28.

55 This tube normally rests in the position shown, as on a stop 29, with the switch open. At the moment the relay switch 20 closes, the cam 22 is arranged substantially as shown in Fig. 1, so that, in a fraction of a second, if desired, i. e., substantially while the switch 20 is being fully

closed, the mercury switch 28 will be tilted and closed. Inasmuch as the switch 14 and consequently the switch 20 are closed each time for one second and the cam 22 is rotated by power at the rate of one revolution in five seconds, it follows that the cam 22 will rotate one-fifth of a revolution while the switch 20 remains closed. Then the switch 20 will open because by that time the switch 14 has opened, thereby de-energizing the relay coil 18 controlling the relay switch 20. However, the circuit through the motor 21 is not broken by virtue of the opening of the switch 20, because, before the switch 20 is opened, the outer surface 22a of the cam 22 has become engaged with the lever 25 and therefore has not only closed the tube switch 28, as explained above, but maintains the switch 28 closed, and it will be observed that the tube switch 28 is in parallel with and therefore bypasses the relay switch 20. The motor 21 therefore continues in operation, as does the cam 22, and the lever 25 continues to ride on the outer surface of said cam.

The cam 22 has a cavity 30, and when the lever 25 drops from the "break" point 31 into the cavity, the tube switch 28 swings to open position, opening the motor circuit, the relay switch 20 at such time being open. Since the cam 22 is turned by the motor at the rate of once in five seconds, whereas the switch 20 is closed for only one second and at intervals of fifteen minutes, in the example chosen for illustration, and since that interval is not completed until after the projection of the lever 25 into the cavity 30, the opening of the motor circuit at such projection is assured.

The motor 21 does not stop immediately, but, rather, together with the reduction gearing and cam 22, it coasts to such an extent as to rotate the cam 22 a fraction of a turn. The cam 22 is so designed that it will hold the switch 28 closed longer than one second, i. e., longer than the switch 20 is closed. The travel of the cam 22 from the end of the coast of the cam to the time of closing of the switch 28 should consume less than one second because, as noted above, the rotation of the cam at this point results from the closing of the relay switch 20, and it is necessary that the lever 25 reach the outer surface of the cam and thereby close the switch 28 before the switch 20 opens, as stated above. Otherwise the cam would stop when the switch 20 opens, and thus the agitator, presently to be described, would not be operated as often as it should, i. e., as often as the switch 20 closes. The coasting cavity 30 in the cam 22 may be designed by cut and try methods, simply by running and stopping the motor 21 a few times and observing the travel of the cam 22 during each coasting period.

Connected to the cam 22 in any suitable manner, as indicated diagrammatically at 33, is a crank disc 34 having a crank pin 35 to which is joined a pitman 37 passing through an opening 38 in the outer wall 39 of a compartment 41 which may intervene portions of the wind-box 42. The wall 39 is preferably detachably connected, as to the wind-box, to render the interior of the compartment accessible for inspection, adjustment and repair. The pitman in turn is joined as at 43 to an agitator bar 45 pivotally suspended as at 46 outside of the burner or retort 47, to which a coal feed tube 49 leads. A rubber, leather or other suitable flexible boot 75

or shroud 50 is attached about the opening 38 and has a preferably air-tight fit about the pitman 37 so as to move therewith and yet keep dust and the like from entering the compartment through the opening 38. The agitator 45 comprises a driving part 52, to which the pitman is connected, and a driven part in the form of a prong or prod 53. The part 52 is adapted to move entirely within the compartment, but the prod is adapted to protrude completely through an opening 54, preferably adjacent the feed tube 49, and to be completely withdrawn from the burner to a position where it is protected from the heat, as shown respectively in full and dotted lines in Fig. 1. The tip or end 56 of the prod, where it enters the burner, i. e., at the opening 54, is preferably sufficiently below the bottom of the coke tree 57 to enable said tip to force up a substantial quantity of green coal as well as break up the tree. The prod is arranged preferably so as to strike the tree substantially at the axis of the tree, and substantially crumbles the tree at each operation.

A breaking of any part of the tree will effect the breaking up of substantially all of it. The burner wall at the opening 54 is preferably sufficiently close to the prod 53 to wipe riddlings, ash, etc., from the prod upon each return movement of the latter, thus substantially preventing any foreign matter from entering the compartment through the opening.

It will be observed that the opening 54 extends outwardly somewhat, providing a passage for the escape into the feed tube 49 of any riddlings, ash, etc., which may tend to enter the compartment 41 where the prod is located. This opening is not sufficiently wide to allow coal to enter the compartment.

Referring again to the cam 22, it will be observed that the outer surface of the cam maintains the switch 28 closed notwithstanding the fact that the switch 20 is open, and thereby closes the circuit of the motor 21 which accordingly continues to rotate the cam 22 and of course the crank disc 34. When the bell crank lever 25 jumps off the "break" point 31 of the cam 22, the switch 28 opens, and since the switch 20 at such time is open and will continue to be open for a while thereafter, the circuit including the motor 21 is opened. As stated before, the reduction gearing will coast until the parts are arranged as shown in Fig. 1 and, during this coasting, the agitator prod 53 is withdrawn completely from the retort 47. The cam 22 cannot stop except in the position shown in Fig. 1, and consequently the agitator prod 53 cannot stop until its end 56 is withdrawn to a position where only green coal is located.

With reference to the relative operations of the switches 20 and 28, it is to be noted that it is desirable to have the agitator 45 rest between agitations to give its prod 53 an opportunity to cool, and this is made possible by withholding closing of the switch 20 for an interval after the cam 22 stops. Unless this is done the agitator will be in continuous motion, which may be unnecessary or undesirable. By providing the arrangement above noted by way of example, it is apparent that the period of a complete cycle of continuous motion of the cam, and hence of the agitator, is somewhat over five seconds, due to the coasting time which obviously is slower than the motor running time. With the switch 20 closing every fifteen minutes, for example, the interval

of rest will be short of fifteen minutes by slightly more than five seconds. By varying the frequency of closing the switch 20, as by varying the speed of the cam 11 or the number of its vanes 12, or the speed of rotation of the cam 22 or the length of the cavity 30, or making any other suitable changes, the waiting interval can be made once or more per hour or once every few hours or otherwise as desired.

Fig. 2 shows more or less diagrammatically the general assembly of a stoker 60, a furnace 61 and a part of the coke-tree agitator mechanism. The agitator and its operating mechanism are outside and readily accessible for repair or other attention, for which purpose the wall 39 is preferably removably mounted. As will be appreciated from the foregoing, the agitator and its operating mechanism are entirely independent of the stoker and hence may be stopped and repaired without interfering with the operation of the stoker, and likewise the stoker may be stopped or given any desired attention without affecting the operation of the agitator or its operating mechanism.

Various modifications may suggest themselves to those skilled in the art without departing from the spirit of our invention, and, hence, we do not wish to be restricted to the specific form shown or uses mentioned.

We claim:

1. A device of the class described, comprising a circuit including motive means, a pair of normally open switches, each in parallel with the other and in series with said motive means, a relay operative intermittently to close one of said switches, means rendered operative by the closing of the relay switch to close the other switch,

means for maintaining said other switch closed for a limited period after said relay switch opens, a furnace retort adapted to consume solid fuel having coke-tree forming characteristics, and means operatively connected to said motive means and projectable thereby into and out of engagement with a coke-tree in said retort while said other switch is closed, said projectable means being out of engagement with the tree when said other switch is open.

2. A device of the class described, comprising a solid fuel retort, a coke-tree breaker projectable into and out of engagement with a tree in said retort, motive means for said breaker, a control for said motive means, means momentarily operative for initiating operation of said motive means, said motive means including means operative for maintaining said control in operation for a period during which said breaker moves into and out of engagement with the tree, and means for rendering said control inoperative at the end of said period.

3. A device of the class described, comprising a solid fuel retort, a coke-tree breaker projectable into and out of engagement with a tree in said retort, motive means for said breaker, means affording a supply of energy to said motive means, means connecting said supply to said motive means, rendering the latter operative to project said breaker into engagement with the tree, means for disconnecting said supply from said motive means during said engagement, said motive means coasting upon such disconnection to such an extent as to withdraw said breaker out of said retort.

ARTHUR K. KNUDSEN.
